UNITED STATES PATENT OFFICE.

CHARLES E. STOLTZ, OF ST. LOUIS, MISSOURI, ASSIGNOR TO MANCHA STORAGE BATTERY LOCOMOTIVE COMPANY, OF ST. LOUIS, MISSOURI, A CORPORATION OF DELAWARE.

MULTIPLE FUSE.

Application filed April 16, 1925. Serial No. 23,595.

This invention relates to multiple fuses of the type that comprise a plurality of fuses, and a carrier or supporting device for said fuses that is adapted to be moved so as to bring a selected fuse into operative relationship with an electric circuit.

In conventional multiple fuses of the general type above referred to the carrier can be moved when the co-operating contacts on the carrier and in the electric circuit are engaged. This is objectionable for two reasons:

(1) Because the relative movement of the stationary contacts of the electric circuit and the co-operating fuse contacts on the carrier is apt to create an electric arc which burns the contacts; and

(2) Arcing of the electric current inside of the housing of the fuses is extremely dangerous when the fuse is used on some kinds of apparatus, for example, an electric storage battery mine locomotive.

The main object of my invention is to provide a multiple fuse which is so constructed that the carrier cannot be moved to bring a new fuse or perfect fuse into operative relationship with the electric circuit when any of the fuse contacts on the carrier are engaged with the contacts in the circuit, thereby eliminating the possibility of the current arcing, as so often occurs in the conventional multiple fuse when the position of the fuse carrier is changed. As arcing of the current is prevented, the life of the contacts is prolonged and the danger of a fire or an explosion is reduced to the minimum.

Another object is to provide a multiple fuse of novel construction which is so designed that there is no possibility of the current arcing during the operation of inspecting or replacing the fuses.

Another object is to provide a multiple fuse in which the fuse carrier is normally held in an operative position by a locking device, which, upon being manipulated preparatory to shifting the carrier to bring a perfect fuse into operative relationship with the electric circuit, results in the fuse contacts on the carrier and the co-operating stationary contacts in the electric circuit being separated with a quick break.

Another object is to provide a substantially flame and gas proof multiple fuse in which the co-operating parts of same are

constructed in a novel manner that facilitates the removal of the fuse carrier from the housing for replacement or inspection of the fuses and the co-operating contacts. Other objects and desirable features of my invention will be hereinafter pointed out.

Figure 1 of the drawings is a side elevational view, partly in vertical longitudinal section, of my improved multiple fuse, showing the carrier in the position it occupies when co-operating contacts on the carrier and in the circuit are engaged.

Figure 2 is a front elevational view of said fuse, showing the parts arranged in the position shown in Figure 1.

Figure 3 is a longitudinal sectional view, showing the fuse carrier in the position it occupies when the stationary contacts in the circuit are disengaged from the co-operating contacts on the carrier.

Figure 4 is a front elevational view, illustrating the parts arranged in the position shown in Figure 3.

Figure 5 is a sectional view, taken on the line 5—5 of Figure 4, looking in the direction indicated by the arrows.

Figure 6 is a transverse sectional view, taken on the line 6—6 of Figure 1, looking in the direction indicated by the arrows; and

Figure 7 is a transverse sectional view, taken on the line 7—7 of Figure 3.

Referring to the drawings which illustrate the preferred form of my invention, A designates the housing of my improved multiple fuse, which preferably comprises a cylindrical side wall closed at its rear end by an integral back wall 1 and provided at its front end with an externally-screw-threaded flange 2 that is adapted to receive a locking ring 3 which retains the removable cover 4 of the housing in its closed position. The fuse carrier B preferably consists of a substantially disk-shaped member formed of insulating material and rigidly connected to a shaft 5 that projects forwardly through the removable cover 4 of the housing, said shaft being surrounded by an inwardly-projecting bearing 6 on the inner side of said cover. At the rear end of said shaft is an extension or reduced portion 5* that projects into a tubular guide 7 on the back wall 1 of the housing. The shaft 5 is mounted in such a way that it can be rotated so as to arrange a

selected fuse on the carrier in operative relationship with the electric circuit and also moved longitudinally of the bearings 6 and 7 which sustain it so as to disengage two of 5 the fuse contacts on the carrier B from the co-operating contacts of the electric circuit and hold the fuse carrier B in such a position that it will be impossible for the current to arc between any of the contacts on 10 the carrier and those in the electric circuit when the position of the carrier is thereafter changed to bring a different fuse, for example, a perfect fuse, into operative relationship with the electric circuit. Preferably, 15 the fuse carrier B, the shaft 5 of same and the removable cover 4 of the housing A are combined as a single unit so as to cause the fuse carrier to be completely withdrawn from the housing A when the cover 4 is 20 removed.

The supply wires α of the electric circuit are connected to stationary contacts 8 that are mounted on a disk-shaped insulator C that is connected to the rear wall 1 of the 25 housing by concealed fastening devices 9 and said insulator is held spaced away from said wall and from the cylindrical side wall of the housing by lugs 10 on said walls, as shown in Figure 3. The contacts 8 of the 30 electric circuit are set flush with the front face of the insulator C and are provided with binding screws 11 or the like for securing the supply wires α to said contacts. As shown in Figures 3 and 7, the contacts 35 8 are arranged at the lower side of the housing A and the supply wires α are led into said housing through stuffing boxes 12 on the back wall 1 of the housing.

The fuse carrier B is provided with a plurality of movable contacts to which fuses are detachably connected. In the form of 40 my invention herein shown said carrier is equipped with four contacts 13 arranged so that three fuses 14, 14^a and 14^b can be detachably connected to the same, as shown in Figure 6. When the fuse carrier is in the position shown in said figure the fuse 14 is in operative relationship with the electric circuit and both of the fuses 14^a and 14^b 45 are inoperative. If the fuse 14 becomes defective, the carrier B can be turned to the right to bring the fuse 14^a into operative position, or turned to the left to bring the fuse 14^b into operative position, the contacts 13 on the carrier to which the fuses are connected being so disposed that at least 50 two of said contacts will always be in alignment with the contacts 8 of the electric circuit whenever the fuse carrier is arranged in one of its three different operative positions. Preferably, the contacts 13 on the fuse carrier are mounted in such a manner 55 that they are capable of moving relatively to the carrier in a direction parallel to the 60 longitudinal axis of the contacts 8 and 13,

and they are backed up by springs 15, as shown in Figures 1 and 3, so as to reduce the tendency of the electric current to arc when the fuse carrier is moved forwardly preparatory to turning the carrier to bring 70 a different fuse thereon into operative relationship with the circuit. The portion of the shaft 5 that passes through the bearing 6 is preferably provided on its exterior with grooves 16 so as to tend to eliminate the possibility of gas entering the housing or a flame escaping from the housing through the bearing 6, and if desired, the fuse carrier can be provided with a forwardly-projecting, annular flame shield 17 that surrounds 75 the shaft bearing 6 on the cover 4 when the fuse carrier is moved forwardly to open the electric circuit. By constructing the housing and the fuse carrier shaft in this manner I make the device practically flame and 80 gas proof.

As previously stated, one of the objects of the invention is to prevent the electric current from arcing, due to relative movement of the contacts on the fuse carrier and the contacts of the electric circuit. In the form of my invention herein illustrated this is accomplished by equipping the device with a locking element, which, when arranged in its operative position, holds the 95 fuse carrier in one of its three operative positions and prevents the fuse carrier from being turned either to the right or to the left, and combining said locking element with the carrier and with a spring in such 100 a way that the fuse contacts on the carrier will be separated with a quick break from the contacts of the electric circuit when said locking element is moved into its inoperative position. In view of the fact that 105 the fuse carrier can be turned only when all of the contacts on said carrier are spaced far away from the stationary contacts to which the supply wires of the electric circuit are connected, there is no danger of 110 the contacts being burned or damaged by arcing of the current, resulting from relative movement of the fuse contacts and circuit contacts during the operation of bringing a new fuse or perfect fuse into operative position with relation to the electric circuit. Moreover, the device is so constructed that it is impossible for the current to arc between the contacts during the 115 operation of bodily removing the fuse carrier from the housing A, because the cover of the housing cannot be removed without first separating the contacts on the carrier from the contacts of the circuit. In the 120 form of my invention herein illustrated the shaft 5 of the fuse carrier is provided at its front end with a handle or knob D, and a coiled expansion spring 18 is mounted on the front end portion of the shaft 5 between 125 said knob and the removable cover 4 of 130

the housing, so as to exert pressure on the shaft 5 in a direction tending to move it forwardly relatively to said cover, and thus hold the fuse carrier B spaced a considerable distance away from the insulator C that carries the stationary contacts 8, as shown in Figure 3, the knob D being rigidly connected to the shaft 5, as, for example, by means of a pin 19, and said knob being provided on its interior with a socket or a recess that houses the spring 18. The locking element previously referred to is designated in the drawings by the reference character E and preferably consists of a lever pivotally mounted on a forwardly-projecting lug 20 on the outside of the cover 4 of the housing and constructed in such a manner that when it is arranged in its operative position, shown in Figures 1 and 2, it will hold the co-operating contacts on the carrier and in the circuit in engagement and also act as a stop or abutment that co-operates with a part on the handle D to prevent the fuse carrier B from being turned, and when it is arranged in its inoperative position, shown in Figures 3 and 4, it will permit the spring 18 to expand, thus separating said contacts, and will not interfere with the rotary movement of the handle D and the fuse carrier shaft 5 connected thereto to bring the contacts of one or the other of the fuses on said carrier into alignment with the contacts 8 of the electric circuit. In the device herein shown the locking element E is provided at its inner end with a cam portion 21 whose peripheral edge is adapted to engage a flange 22 at the inner end of the handle D when said locking element is swung upwardly from the position shown in Figure 3 into the position shown in Figure 1, and thus exert pressure on the fuse carrier shaft 5 in a direction to compress the spring 18 and move the fuse carrier inwardly towards the insulator C, so as to cause one pair of contacts 13 on the carrier B to engage the co-operating contacts 8 of the electric circuit. When the locking element E is in this position, namely, its operative position, as shown in Figures 1 and 2, a flat face 23 on one side of the cam portion 21 will be positioned in close proximity to one of a plurality of flat faces 24, 24^a and 24^b on the handle D, as shown in Figure 2, thereby preventing the handle D and the parts connected to same from being turned in either direction, due, of course, to the fact that the flat face 23 on the locking element E is positioned in such close proximity to one of said flat faces on the handle D that any attempt to turn said handle causes the portion of the handle on which said flat faces are formed to be brought squarely against the locking element E. When it is desired to turn the fuse carrier B to bring a different fuse, for example, a perfect fuse, into operative relationship with the electric circuit after one of the other fuses on said carrier has become defective, the locking element E is swung downwardly into the position shown in Figure 4, thereby causing the cam 21 on said locking element to move out of engagement with the flange 22 on the handle D, whereupon the spring 18 expands and moves the fuse carrier B, the shaft 5 and the handle D longitudinally or outwardly into the position shown in Figure 3, wherein it will be noted that the fuse contacts 13 on the carrier are spaced a considerable distance away from the co-operating contacts 8 of the electric circuit. When the locking element E is arranged in this position, namely, its inoperative position, a flat face 25 on said locking element bears against the flange 22 on the handle D, and thus acts as an abutment that limits the outward movement of said handle and the parts controlled by said handle. In order that the handle D and fuse carrier shaft 5 may be rotated, either to the right or to the left, when the locking element E is arranged in its inoperative position, the portion on said locking element that contains the cam 21 and the flat side face 23, is so disposed that when the locking element is in this position, sufficient clearance is provided between the flat face 23 and the part on the handle that contains the flat faces 24, 24^a and 24^b to permit said handle to be turned freely. In other words, when the locking element E is in its operative position, a portion on said locking element is disposed in such relation with a portion on the handle D that it is impossible to rotate said handle either to the right or to the left, but when said locking element E is moved into its inoperative position, the relationship between said co-operating portions is changed sufficiently to permit the handle D to be turned in either direction.

If the carrier B is equipped with three fuses, as herein illustrated, the handle D is provided with three flat faces 24, 24^a and 24^b so that the flat face 24 will be operative or disposed in parallel relationship with the co-operating flat face 23 on the locking element E when the fuse 14 on the carrier is in its operative position, the flat face 24^a on the handle D will be disposed in operative relationship with the face 23 on the locking element when the fuse 14^a on the carrier is operative, and the flat face 24^b on the handle D will be in operative relationship with the face 23 on the locking element when the fuse 14^b on the carrier is operative. Any suitable means can be used for enabling the operator in charge of the device to know which one of the fuses on the carrier is in operative relationship with the electric circuit without removing the cover 4 of the housing A. In

the form of my invention herein illustrated the handle D of the fuse carrier is provided with a radially-disposed projection or hand 26 and the cover 4 is provided on its outer face with three ribs or other suitable elements 27, 27^a and 27^b that co-operate with said hand 26 to denote the position of the fuses on the carrier B.

The spring 18, previously referred to, that 10 is used to move the fuse carrier shaft 5 forwardly, is preferably made strong enough so that it will separate the co-operating contacts on the carrier B and insulator C with a quick break when the locking element E is 15 moved into its inoperative position, shown in Figure 3, thereby preventing the current from arcing during the operation of moving the fuse carrier B forwardly into its inoperative position, shown in Figure 3, preparatory to rotating said fuse carrier to bring a 20 perfect fuse into operative relationship with the electric circuit. The springs 15 that back up the fuse contacts 13 on the carrier B exert sufficient pressure on said contacts to 25 insure them bearing snugly against the co-operating stationary contacts 8 to which the supply wires α of the electric circuit are connected, and said springs 15 also tend to eliminate arcing during the operation of moving 30 the fuse carrier forwardly into its inoperative position, due to the fact that they cause the fuse contacts 13 to remain in engagement with the co-operating stationary contacts 8 while the cam 21 on the locking element E 35 is moving over the flange 22 on the handle D of the fuse carrier. In other words, the slight forward movement of the carrier B away from the contact insulator C during the operation of moving the locking element E 40 into its inoperative position, will not cause the current to arc between the contacts 8 and 13, due to the fact that the springs 15 hold said contacts pressed tightly together until the locking element E has reached such 45 a position that the spring 18 is free to expand and throw the fuse carrier B forwardly with a quick movement. While I have herein illustrated the carrier B equipped with fuses of the link type that are detachably 50 connected by nuts to the contacts 13 on the carrier, as shown in Figures 1-3 and 6, it will, of course, be obvious that various other types or kinds of fuses can be used without departing from the spirit of my invention. 55 Means is preferably provided for preventing an unauthorized person from removing the cover 4 of the housing, such, for example, as a retaining pin F that is adapted to be arranged in a pair of perforated lugs 28 60 on the outside of the housing A in such a position that one end of said pin is positioned in a notch 29 in the peripheral edge of the removable retaining ring 3 that surrounds the cover 4 of the housing, said pin F being 65 provided with a stop 30 that bears against

one of the lugs 28 and also provided with a hole through which the hasp of a padlock 31 can be inserted, so as to prevent said pin from being disengaged from the lugs 28 or moved in a direction to withdraw the end 70 of same from the notch 29 in the cover retaining ring 3.

A multiple fuse of the construction above described is of such simple design that it can be manufactured at a low cost; it is of such 75 design that the contacts are not liable to be burned or injured by arcing of the electric current, due, of course, to the fact that it is constructed in such a manner that the fuse carrier cannot be turned whenever any of 80 the contacts on same are engaged with the contacts in the circuit, and the cover of the housing A cannot be removed without first separating the contacts on the carrier from the contacts of the electric circuit; the housing of the device is practically flame and gas 85 proof, and a simple means is provided on the exterior of the housing for indicating the position of the fuses on the carrier.

Having thus described my invention, what 90 I claim as new and desire to secure by Letters Patent is:

1. A multiple fuse, comprising a carrier provided with a plurality of fuses, any one of which is adapted to be arranged in operative relationship with an electric circuit by moving the carrier in a certain manner, co-operating contacts on said carrier and in said circuit, a part combined with said carrier, a manually operable locking device, which, when arranged in its operative position, co-operates with said part to prevent movement of the carrier, and means for automatically separating the co-operating contacts on the carrier and in the electric circuit 105 when said locking device is rendered inoperative.

2. A multiple fuse, comprising a rotatable carrier provided with a plurality of fuses, any one of which is adapted to be brought 110 into operative position with an electric circuit by rotating the carrier, cooperating contacts on said carrier and in said circuit, a part connected to said carrier to turn with same, and a manually-operable locking device that co-operates with said part to prevent the carrier from being rotated when the contacts of the electric circuit are in engagement with one pair of fuse contacts on the carrier.

3. A multiple fuse, comprising a manually-operable carrier provided with a plurality of fuses, any one of which is adapted to be brought 115 into operative relationship with a circuit by moving the carrier in a certain manner, co-operating contacts on said carrier and in said circuit, and a movable, manually-operable locking means that normally holds the carrier against movement in a direction to change the relationship between the fuse thereon and the electric circuit, con- 120 125 130

structed so that it has to be moved bodily into an inoperative position before the contacts of the operative fuse and the co-operating contacts of the electric circuit can separate and before the carrier can be moved to change the relationship between the fuses thereon and the electric circuit.

4. A multiple fuse, comprising a carrier provided with a plurality of fuses, any one of which is adapted to be brought into operative relationship with an electric circuit by moving the carrier in a certain manner, co-operating contacts on said carrier and in said circuit, a manually operable locking element that normally prevents the carrier from being moved in the manner referred to and which is adapted to be rendered inoperative before such movement can be imparted to the carrier, and means for causing the co-operating contacts on the carrier and in the electric circuit to be separated with a quick break simultaneously with the movement of said locking element into its inoperative position.

5. A multiple fuse, comprising a manually-operable rotatable carrier provided with a plurality of fuses, any one of which can be brought into operative relationship with an electric circuit by rotating the carrier, co-operating contacts on said carrier and in said circuit, a manually-operable locking element, which, when arranged in its operative position, prevents the carrier from being turned and which, when arranged in its inoperative position, permits the carrier to be turned, and means for insuring the contacts of the electric circuit being separated from the co-operating contacts on the carrier when said locking element is in a position to permit the fuse carrier to be turned.

6. A multiple fuse, comprising a carrier provided with a plurality of fuses, any one of which is adapted to be brought into operative relationship with an electric circuit by moving the carrier in a certain manner, co-operating contacts on said carrier and in said circuit, a manually-operable means which is normally operative to prevent the carrier from being moved in the manner referred to and which is adapted to be moved manually into an inoperative position to permit such movement of the carrier, and an independent means for separating the co-operating contacts in the electric circuit and on the carrier when said manually operable means is rendered inoperative.

7. A multiple fuse, comprising a rotatable carrier provided with a plurality of fuses equipped with contacts, co-operating contacts in an electric circuit, a resilient means that exerts pressure on said carrier in a direction tending to effect the separation of the contacts of the electric circuit and the contacts of the operative fuse on the carrier, and an independent manually-operable means that normally holds the co-operating contacts

on the carrier and in the electric circuit in engagement with each other, constructed so that the carrier cannot be turned when said co-operating contacts are in engagement.

8. A multiple fuse, comprising a rotatable carrier provided with a plurality of fuses, any one of which can be brought into operative relationship with an electric circuit by turning the carrier, means for normally holding the carrier in such a position that one of the fuses thereon will be operative, means for preventing the carrier from being turned when it is in said position, and a resilient means for bodily moving the carrier in a direction to destroy the operative relationship between all of the fuses thereon and the electric circuit when the means first referred to is rendered inoperative.

9. A multiple fuse, comprising a rotatable carrier provided with a plurality of fuses connected to contacts on the carrier, co-operating contacts arranged in an electric circuit, a resilient means that tends to move the carrier in a direction to separate the fuse contacts on same from the contacts of the electric circuit, and a manually-operable device for moving the carrier in a direction to bring the contacts of one fuse on the carrier into engagement with the contacts of the electric circuit, constructed so that it prevents the carrier from being turned when said co-operating contacts are in engagement with each other.

10. A multiple fuse, comprising a rotatable carrier provided with a plurality of fuses equipped with contacts, any one of which can be brought into operative relationship with an electric circuit by turning the carrier, contacts in said circuit that are adapted to co-operate with the contacts of said fuses, said carrier being mounted so that it can be moved longitudinally to disengage the contacts of the electric circuit from the contacts of the operative fuse on the carrier, a manually-operable locking element for moving the carrier longitudinally in one direction, a spring for moving the carrier longitudinally in the opposite direction, and a part connected with the carrier and adapted to co-operate with said locking element for holding the carrier against rotary movement when the contacts of the circuit are in engagement with the contacts of the operative fuse on the carrier.

11. A multiple fuse, comprising a rotatable carrier mounted in such a way that it can be shifted longitudinally of its axis of movement, fuses on said carrier connected to contacts on the carrier, stationary contacts forming part of an electric circuit, a spring for moving the carrier longitudinally in a direction to separate the contacts of the operative fuse from the contacts of the electric circuit, a manually-operable device for moving the carrier longitudinally in op-

position to said spring and for holding the contacts of the operative fuse on the carrier in engagement with the contacts of the electric circuit, and a part combined with the carrier and arranged so that it will co-operate with said manually-operable device to hold the carrier against rotary movement when any of the co-operating contacts on the carrier and in the supply circuit are engaged.

12. A multiple fuse, comprising a housing, a rotatable carrier in said housing provided with a plurality of fuses, fuse contacts on said carrier, co-operating fuse contacts in an electric circuit, a supporting shaft for said carrier mounted in the housing in such a way that it can rotate and also move longitudinally of its axis, a manually-operable device on the exterior of the housing for moving said shaft longitudinally in a direction to cause the fuse contacts on the carrier to engage the contacts of the electric circuit, a spring for moving said shaft in the opposite direction, and a part on said shaft that is adapted to co-operate with said device to prevent said shaft from being rotated when said co-operating contacts are engaged.

13. A multiple fuse, comprising a housing, a fuse carrier arranged inside of said housing and provided with fuse contacts that are adapted to co-operate with contacts in an electric circuit, a supporting shaft for said carrier mounted in said housing in such a way that it can rotate and also move longitudinally of its axis, a pivotally mounted locking device on the exterior of the housing provided with a cam, a member connected to said shaft and provided with a portion that is adapted to be engaged by said cam to move said shaft longitudinally in one direction, a spring for moving said shaft longitudinally in the opposite direction, and co-operating surfaces on said locking device and on the member on said shaft for holding said carrier against rotary movement when the fuse contacts thereon are in engagement with the contacts of the electric circuit.

14. A multiple fuse, comprising a housing, a fuse carrier in said housing provided with spring-pressed fuse contacts, contacts in an electric circuit adapted to be engaged by said fuse contacts, a supporting shaft for said carrier projecting forwardly through an opening in the housing, a handle on the outer end of said shaft for turning same, a spring for moving said shaft in a direction to separate the fuse contacts thereon from the contacts of the electric circuit, a manually-operable device on the exterior of the housing for moving said shaft longitudinally in opposition to said spring, and co-operating surfaces on said device and on said handle for preventing the fuse carrier

from being turned when any of the fuse contacts thereon are in engagement with the contacts of the electric circuit.

15. A multiple fuse, comprising a housing, a carrier in said housing provided with a plurality of fuses, any one of which can be arranged in operative position with relation to an electric circuit by turning the carrier, a supporting shaft for said carrier mounted in said housing in such a way that it can rotate and also move longitudinally of its axis, a handle on said shaft arranged on the outside of the housing, a locking device on the exterior of the housing provided with a cam that is adapted to engage a part on said handle so as to move said shaft longitudinally to arrange one of the fuses thereon in operative position in the electric circuit, a spring for moving said shaft in the opposite direction, and a plurality of surfaces on said handle corresponding in number to the number of fuses on the carrier, any one of which is capable of co-operating with said locking device to hold the carrier against rotary movement when one of the fuses on the carrier is in operative position.

16. A multiple fuse, comprising a housing, a removable cover on said housing, a carrier arranged inside of said housing and provided with a plurality of fuses, any one of which can be arranged in operative position in an electric circuit by turning the carrier, a supporting shaft for said carrier, bearings on the cover of the housing and on the opposed wall of the housing for supporting said shaft, a handle connected to said shaft at a point outside of the housing, a pivotally mounted locking device on said cover provided with a cam that is adapted to be moved into engagement with a part on said handle to move said shaft longitudinally in a direction to carry one of the fuses on the carrier into operative position in the electric circuit, a spring for moving said shaft longitudinally in the opposite direction, co-operating surfaces on said handle and locking device for holding the carrier against rotary movement when one of the fuses thereon is electrically connected with the circuit, and means on the exterior of the housing which indicate the position of the fuses on the carrier.

17. A multiple fuse, comprising a housing, a removable cover at the front end of said housing, a bearing projecting inwardly from said cover, a bearing on the back wall of the housing, a rotatable shaft reciprocatingly mounted in said bearings, a carrier connected to said shaft, a plurality of spring-pressed fuse contacts on said carrier, fuses detachably connected to said contacts, an insulator stationarily mounted inside of said housing and provided with contacts to which the wires of an electric circuit are

connected, a handle connected to said shaft at a point outside of said housing, a spring surrounding said shaft between said handle and the removable cover of the housing for moving said shaft longitudinally in one direction, a locking device pivotally mounted on the outside of said cover and provided with a cam, a part on said handle that is adopted to be engaged by said cam to effect movement of said shaft in opposition to said spring, co-operating surfaces on said locking device and handle for holding the fuse carrier against rotary movement when one of the fuses on said carrier is electrically connected with the electric circuit, and co-operating means on said handle and on the cover of the housing for indicating the position of the fuses on the carrier. 15

CHARLES E. STOLTZ.
